DESIGN.

—o—
J. L. FOLSON.

CARPET.

No. 18,232.

Patented Apr. 3, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,232, dated April 3, 1888.

Application filed January 26, 1888. Serial No. 262,070. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of a number of coral-like figures disposed irregularly over the surface of the carpet. These figures vary somewhat in form and size.

20 Figure A is circular in character, and has a central solid portion from which coral-like

arms project or radiate with more or less regularity. These coral-like arms vary somewhat in length.

Figure B is square in general form, and has 25 a central solid portion from which broad coral-like arms or masses project. These broad arms or masses themselves have short projecting arms or portions forming an irregular curving outline. This figure is ornamented by 30 several overlying coral forms.

Figures A and B and the other figures are all arranged upon a watered ground.

What I claim as new, and desire to secure by Letters Patent, is— 35

The design for carpets, consisting of the design substantially as shown.

JAS. L. FOLSOM.
